H. HAFKESBRINK,
WING PUMP,
APPLICATION FILED AUG. 25, 1921.

Patented Jan. 17, 1922.

Fig. 1.

UNITED STATES PATENT OFFICE.

HEINRICH HAFKESBRINK, OF BERLIN-FRIEDENAU, GERMANY.

WING PUMP.

1,404,116.

Specification of Letters Patent. Patented Jan. 17, 1922.

Application filed August 25, 1921. Serial No. 495,223.

To all whom it may concern:

Be it known that I, HEINRICH HAFKESBRINK, a citizen of the German Republic, residing at Berlin-Friedenau, Germany, have 5 invented certain new and useful Improvements in Wing Pumps, (for which I have filed an application in Germany on the 29th of November, 1919,) of which the following is a specification.

10 This invention relates to a wing pump which is distinguished by simple construction and by great efficiency.

In order that the invention may be clearly understood, I shall proceed to describe the 15 same with reference to the form of construction shown by way of example on the accompanying drawing, wherein:—

Fig. 1 is a cross section through the suction side of the pump.

20 Fig. 2 is a longitudinal section, and Fig. 3 is a partial cross section through the discharge side of the pump.

In a circular casing 1 an oscillable wing 2 is mounted upon a wing shaft 3. In the 25 lower part of the pump the suction port 4 and the discharge 5 are arranged, the discharge channel 7 being cast upon the rear wall 6 of the casing. This discharge channel 7 terminates with its orifice 8 in the discharge side of the casing and it presents at the middle an enlargement 9 so that at 30 this point the rear wall 6 of the casing and the wall of the discharge channel can be connected by a cast partition 10 without impeding the outflow of the liquid. This partition 10 serves as bearing for one end of the wing shaft 3, whose other end is journaled in the cover 11 of the casing.

A V-shaped comparatively narrow valve 40 support 12 with suction flaps 13 and pressure flaps 14 is arranged over the suction port and discharge port, all the flaps or only the pressure flaps being pressed upon their seats by springs 15. The interval between the suction side and the discharge side within the valve support is separated by 45 a partition 16. It is essential that the valve support 12 is removably mounted in the valve casing and that it is secured in its position only by means of small pins, stops or the like.

The pump is driven by a toothed sector 17 connected with the pump handle 18 and gearing with a pinion 19 keyed upon the 50 wing shaft. The toothed sector 17 is pivotably mounted upon a pin 20 which is fixed

either in the casing or, as shown on Fig. 1, on the cover 11.

This drive has the advantage that with a comparatively small oscillation of the 60 pump handle a full stroke of the wing 2 through about 300° is obtained so that the inner space of the pump is completely utilized.

The packing of the wing against the valve 65 support 12 is effected by a packing 21 the sides of the valve case being packed by the pressing on of the cover.

I claim:—

1. An improved wing pump comprising 70 in combination a circular casing having a discharge port and a suction port, a discharge channel cast in one piece with the rear wall of said casing communicating with said discharge port, a removable valve 75 support, pressure flaps and suction flaps on said valve support, a partition dividing said valve support, an oscillating wing, a pump handle, an oscillating sector connected with said handle, a pump shaft and a pinion 80 keyed upon said shaft and gearing with said toothed sector.

2. An improved wing pump comprising 85 in combination a circular casing having a discharge port and a suction port, a discharge channel cast in one piece with the rear wall of said casing communicating with said discharge port, an enlargement at the middle of said discharge channel, a cast partition connecting the rear wall of said 90 casing and the wall of said enlarged part of the discharge channel serving as journal, a removable valve support, pressure flaps and suction flaps on said valve support, a partition dividing said valve support, means 95 for securing said removable valve support in its position, an oscillating wing, a pump handle, an oscillating sector connected with said handle, a pump shaft journaled in said cast partition and a pinion of smaller 100 diameter than said toothed sector keyed upon said shaft and gearing with said toothed sector.

3. An improved wing pump comprising 105 in combination a circular casing having a discharge port and a suction port, a discharge channel cast in one piece with the rear wall of said casing communicating with said discharge port, an enlargement at the middle of said discharge channel, a cast 110 partition connecting the rear wall of said casing and the wall of said enlarged part

of the discharge channel serving as journal, a packing in the valve support for packing the same against said wing, a cover of said casing which tightly packs the sides of said valve support when it is being pressed upon the casing, a removable valve support, pressure flaps and suction flaps on said valve support, a partition dividing said valve support, means for securing said removable valve support in its position, an oscillating wing, a pump handle, an oscillating sector

connected with said handle, a pump shaft journalled in said cast partition and a pinion of smaller diameter than said toothed sector keyed upon said shaft and gearing with said toothed sector. 15

In testimony whereof I affix my signature in presence of two witnesses.

HEINRICH HAFKESBRINK.
